UNITED STATES PATENT OFFICE

WILLIAM R. ROGERS, OF WESTFIELD, NEW JERSEY

AUTOMATIC STOP CONTROL FOR SEWING MACHINES

Application filed June 30, 1931. Serial No. 548,007.

This invention relates to an automatic electric lock stop device especially adaptable for use on power sewing machines; and it has for its object to provide a simple, inexpensive and efficient automatic stop device.

Another object of this device is to provide in the electric lock employed a manual control means for actuating the lock in case of any failure in the current that normally

10 operates the same.

Other objects of this invention will become apparent as the description thereof given hereunder proceeds, reference being had to the accompanying drawings, where-

15 in:

Figure 1 is an elevational view of the automatic stop device as applied to a power sewing machine.

Figure 2 is a sectional view of said device taken on line 2—2 of Figure 1.

Figure 3 is a detail sectional view of the electric lock mechanism taken on line 3—3 of Figure 2.

Figure 4 is a detail sectional view taken 25 on line 4—4 of Figure 3.

Referring to Figure 1, there is shown a sewing machine base 10, a standard 11 carrying the conventional sewing mechanism (not shown) in the cantilever housing 12 30 integral with said standard in the manner well known.

Attached to the underneath portion of the base 10, is a frame 13 comprising vertical arms 14 and 15, lugs 16 for securing the 35 frame to the base, and an horizontal extension 17 on the lower end of the arm 15.

Extending between the arms 14 and 15 and horizontally secured thereto by screws 18 is an electro-magnetic lock 19 of conventional design, provided with binding posts 20. This lock 19 is of the conventional type used on front doors in apartment houses, whereby a button pressed in a distant apartment allows the front door to be 40 pressed open. A similar binding post 21 is attached to the end of the extension 17. Formed integral with the frame 13 are rearwardly extending brackets 22 provided with registering vertical openings 23, adapted to 45 slidably receive a plunger rod 25, said rod

extending below the horizontal extension 17 and upwardly through a suitable opening provided in the sewing machine base 10, terminating short of the lower portion of the housing 12. Secured to the base 10 in any desired manner is a spring seat 26, said seat being provided with an opening through which the plunger rod 25 extends as clearly shown in Figures 1 and 2.

Rigidly attached to the upper and lower ends of the plunger rod 25 are knobs 27 and 28, respectively. A compression coil spring 29 is provided on the rod 25, the purpose of which is to be hereinafter described, said coil spring 29 being seated on the spring seat 26, (Figs. 1 and 2). To adjust the compression of the spring 29 an adjusting collar 30 is provided on the plunger rod 25, the position of which is regulated by the set screw 31.

Connected to the brackets 22 of the frame 13 is a guide member 32 provided with a central vertical slot 33. Working in said slot is a guide screw 34, the threaded end of which is horizontally threaded within the plunger rod 25 and extends beyond the surface thereof for a slight distance as clearly shown in Figure 2, said screw being locked in position by the lock nut 35.

Pivoted to the plunger rod 25 beneath the guide screw 34 is stop member 36, said stop member 36 being of U-cross section, see Figure 3, the arms or side walls of which are mounted on the pivot pin 37 which supports said stop member. To maintain said stop member 36 in operative position a small coil spring 38 is employed, said spring being positioned within said stop member and on the extended end of the guide screw 34, in abutting engagement with the plunger rod 25 so as to constantly urge the stop member outwardly. It is apparent that due to the guide screw 34 working in the guide 35 30 35 40 45 50 55 60 65 70 75 80 85 90 95 100 member 32 that the plunger rod 25 while capable of vertical up and down movement cannot turn.

When the plunger rod 25 is pushed down so that the stop 36 engages the latch 40 of the electric lock 19, the knob 28 on the lower end of the rod 25 will engage the lever 41, thereby closing the clutch 42 so

as to permit operation of the sewing machine. As long as the knob 28 engages the lever 41 in the position shown in Figure 1, power will be delivered to operate the sewing machine in the manner well known.

To stop the sewing machine when there is a break in the thread 45 there is provided a switch 46 of the type disclosed in my Patent No. 1,744,678, granted January 21, 1930, 10 adapted to be closed by a trip member 47 pivotally mounted on the thread pulley 48.

The switch 46 is connected by suitable conductors 49 to a source of electrical supply as per example the battery 50.

15 In case there is a break in the thread when the machine is in operation the trip member 47 will move downward in a counter-clockwise direction closing the switch 46 and thereby energizing the electro-magnets

20 (not shown) in the lock 19. The electro-magnet and lock 19 are of conventional construction such as shown in U. S. patent to Schneider, 1,072,996, Sept. 9th, 1913; Guette, 1,121,090, Dec. 15, 1914; and Weiss, 1,618,738,

25 Feb. 22nd, 1927. Said magnets when energized will draw the trigger 51 (Figure 3) inwardly into alignment with the notch 52 in the latch bar 53, permitting latch bar 53 to be pivoted downwardly about its pivot in

30 a clockwise direction thereby permitting the lever latch 40 to be operated against the action of the torsion spring 54 in the well known manner as the tail on latch 40 is permitted to pass out of the recess shown in

35 dotted outline in the pivot of latch bar 53 in Figure 3. Said lever latch 40 when operating will be swung about its pivots in a counter clockwise direction, as viewed in Figure 2, by the stop 36 pressing upwardly

40 thereagainst until said latch 40 is depressed out of engagement with the stop 36 which will therefore permit the plunger rod 25 to move upwardly under the action of the spring 29 to the dotted position shown in

45 Figure 1. When the plunger rod 25 moves away from the lever 41, the clutch 42 will be released thereby stopping the operation of the sewing machine.

In case it is desired to manually operate 50 the lever latch 40 of the electric lock 19 there is provided a push member 55 slidably positioned in the side walls of the lock 19 (see Figure 4) and provided with a reentrant portion 56 which upon a pull being exerted on the push member 55 will cause the trigger 51 to move inwardly in the manner readily apparent. This push member 55 serves as a safety means to actuate the lock 19 to release the stop 36 in case the electrical 55 supply should fail for any reason.

While a preferred embodiment of automatic stop control has been disclosed, the same is susceptible of various changes within the scope of the appended claims.

60 Having thus set forth and disclosed the

nature of this invention, what is claimed is:

1. In combination with a sewing machine comprising a base and housing, a clutch and a clutch control lever pivoted to the under surface of said base and connected to said clutch, a frame secured to the under surface of said base, an electro-magnetic lock on said frame, a plunger rod slidably mounted on said frame and extending upwardly through said base and downwardly beneath said frame, knobs on the ends of said plunger rod, a stop member pivotally mounted on said plunger rod and adapted to coact with the latch of said lock, guide means on said frame and plunger rod, a compression coil spring on said plunger rod seated on the upper surface of said base, and means on said plunger rod to adjust the compression of said coil spring, said plunger rod when in locked engagement with said electro-magnetic lock having the lower knob thereof in engagement with said clutch control lever to maintain said clutch in operation to transmit power.

2. In combination with a sewing machine comprising a base and housing, a clutch and a clutch control lever pivoted to the under surface of said base and connected to said clutch, a frame secured to the under surface of said base, an electro-magnetic lock on said frame, a plunger rod slidably mounted on said frame and extending upwardly through said base and downwardly beneath said frame, knobs on the ends of said plunger rod, a stop member pivotally mounted on said plunger rod and adapted to coact with the latch of said lock, guide means on said frame and plunger rod, a compression coil spring on said plunger rod seated on the upper surface of said base, and means on said plunger rod to adjust the compression of said coil spring, said plunger rod when in locked engagement with said electro-magnetic lock having the lower knob thereof in engagement with said clutch control lever to maintain said clutch in operation to transmit power, a manually operated push member in said electro-magnetic lock adapted to engage the trigger thereof upon movement of the same to open said lock with a consequent release of the plunger rod.

In testimony whereof I affix my signature.

WILLIAM R. ROGERS.
